UNITED STATES PATENT OFFICE.

WALTER D'ARCY RYAN, OF SCHENECTADY, NEW YORK.

HEADLIGHT.

Application filed September 2, 1924. Serial No. 735,405.

My invention relates to improvements in headlights, and is particularly concerned with improvements in headlights designed for use upon automobiles or other automotive vehicles.

In United States Letters Patent No. 1,484,309, dated February 19, 1924, I have disclosed a headlamp comprising a comparatively shallow reflector, a lens, and a source 10 of light arranged so that while the reflector projects sufficient light forwardly adequately to illuminate the roadway, another portion of the light from the source passes directly through the marginal portions of the lens 15 for illuminating the areas at the sides of the road, immediately adjacent the vehicle and the front portion of the vehicle.

My present invention is concerned with the provision of a headlight having similar 20 characteristics but in which I make use of a reflector of comparatively short focal length, so that the light source is located inside of the plane passing through the edge of the reflector.

Another object of my present invention 25 is to provide a headlight, such as described, comprising means for illuminating certain areas lying to the rear of the headlight, so as to illuminate the roadway in advance of 30 the vehicle when the operator turns into a cross road.

In addition, my invention contemplates the provision of a headlight, such as described, that is simple in construction and 35 economical to manufacture.

Other objects of my invention will appear as this description progresses, reference being had to the accompanying drawings, in which

Figure 1 is a side elevation, partially in section, of my improved headlight;

Figure 2 is a front elevation, portions being broken away; and

Figures 3 and 4 are views similar to Figures 1 and 2, respectively, showing a modified form of my invention.

The embodiment of my invention illustrated in Figures 1 and 2 comprises a casing 2, having a door including a supporting 50 ring 3 that may be hinged, or otherwise attached, to the casing 2 as may be desired. A lens 4 is supported by the ring 3 and held in place by clips 5 secured to the ring. A reflector 6 is mounted in the casing and

carries the centrally disposed socket 7 for receiving the electric lamp 8. The reflector is held in place by the collar 9, that is attached to the casing 2, and the clamping ring 10.

The lens, as shown, is bowl-shaped and disposed with its convex surface outwardly. The thickness of the lens is substantially uniform throughout, as shown in Figure 1.

An annular, conoidal, auxiliary reflector 11 is mounted within the lens 4 and secured in place by the brackets 12, the inner ends of which are clamped between the collar 5 and the lens 4.

The lens 4 has an annular, marginal zone 13 that extends substantially parallel with the axis of the reflector 6. The reflecting surface of the auxiliary reflector 11 is disposed toward, and preferably overlaps, the marginal portions of the reflector 6 in such manner as to reflect the rays reflected by the marginal portions of the reflector 6 through the annular zone 13 of the lens 4. The reflector 11 may be so disposed, relatively to the axis of the reflector 6, that it will reflect the light not only at substantially right angles to the axis of the latter reflector, but will also reflect light to the rear of the headlight, as indicated by the arrows 14. These features of my improved headlight are of very considerable value in that while the major portion of the light is reflected as a beam directly ahead of the vehicle, as indicated by the arrows 15, that part of the light reflected to the side and to the rear of the headlight provides means for illuminating sign posts and other direction indicia located at the sides of the roads, and also illuminates the road ahead of the operator when he turns into a cross road.

The modified form of my invention illustrated in Figures 3 and 4 is similar to Figure 1, except that in the modified form I prefer to make use of a plurality of auxiliary reflectors 16, 17 and 18 that are supported by brackets 19, secured in the same manner as the brackets 12 in Figures 1 and 2. These reflectors progressively increase in width, from the inner one to the outer one, and each one is tilted slightly more than the preceding inner one, so as to provide a comparatively large area, or zone, at the side and to the rear of the headlight.

It will be apparent, from the inspection

of Figure 3, that the auxiliary reflectors intercept some of the direct rays and some of the reflected rays from the source of light and divert these rays to the side of the vehicle.

The auxiliary reflectors 11, 16, 17 and 18 may be plain conoids, or they may be ellipsoidal, hyperboloidal, paraboloidal or have any other suitable curvature.

10 The reflector 6 may be made of metal, glass or any other suitable material, but the auxiliary reflectors are preferably made of sheet metal, having suitable reflecting surfaces disposed toward the main reflector.

15 While I have described the details of construction of the preferred embodiment of my invention, it is to be clearly understood that my invention is not limited to these details, but is capable of other adaptations and 20 modifications within the scope of the appended claims.

Having thus described my invention, what I claim is:

1. A headlight comprising a reflector, the 25 focus of which lies inside the plane of the edge of the reflector, a bowl-shaped lens for said reflector, said lens being substantially uniform in thickness and having a marginal zone lying outwardly beyond the edge of 30 said reflector, said marginal zone being substantially parallel with the axis of the reflector, and a plurality of reflector rings located within said lens and positioned to reflect outwardly through said marginal zone 35 the light reflected from the marginal portions of said reflector, the light reflected from the central portion of said reflector passing through the central openings in said rings, at least one of said rings having a concoidal

reflecting surface disposed toward said reflector.

2. A headlight comprising a reflector, the focus of which lies inside the plane of the edge of the reflector, a lens for said reflector having a marginal zone lying outwardly 45 beyond the edge of said reflector, and a plurality of reflector rings located within said lens and positioned to reflect outwardly through said marginal zone the light reflected from the marginal portions of said 50 reflector.

3. A headlight comprising a casing and a reflector, the focus of which lies inside the plane of the edge of the reflector, a bowl shaped lens for said reflector having a marginal zone lying outwardly beyond the edge of said reflector, said marginal zone being substantially parallel with the axis of the reflector, and an annular reflector ring located within said lens and positioned forwardly of the marginal edge of said reflector and casing to reflect outwardly through said marginal zone the light reflected from the marginal portions of said reflector.

4. A headlight comprising a casing and a reflector, the focus of which lies inside of the plane of the edge of the reflector, a lens for said reflector, and an annular reflector ring located within said lens and positioned forwardly of the marginal edge of said reflector 70 and casing to reflect outwardly through the lateral portions of said lens the light reflected from the marginal portions of said reflector.

In witness whereof, I hereunto subscribe my name this 5th day of August, 1924.

WALTER D'ARCY RYAN.
